UNITED STATES PATENT OFFICE.

ALONZO ALDRICH AND EARL E. BERRY, OF BELOIT, WISCONSIN, ASSIGNEES TO
BELOIT IRON WORKS, A CORPORATION OF WISCONSIN.

REMOVABLE-TYPE FOURDRINIER PAPER-MAKING MACHINE.

Original application filed September 19, 1925, Serial No. 57,272. Divided and this application filed December 8, 1926. Serial No. 153,234.

This invention relates to improvements in a removable table type of Fourdrinier paper making machine.

The embodiment of our invention disclosed in this application was originally disclosed in our co-pending application, Serial No. 57,272, filed September 19, 1925, of which the present application is a division.

It is an object of this invention to provide an improved Fourdrinier construction wherein the table is laterally removable as a unit upon tracks adapted to be permanently associated with the Fourdrinier structure and forming the support for said table unit, while in operative and removed position.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary diagrammatic side elevational view of a Fourdrinier paper making machine, showing a table and supporting structure embodying the principles of this invention.

Figure 2 is a broken plan view of Figure 1, with the table removed to show the supporting structure and tracks.

Figure 3 is an enlarged transverse view taken substantially on line III—III of Figure 2.

Figure 4 is a fragmentary top view of Figure 3.

Figure 5 is an enlarged sectional view taken on line V—V of Figure 4.

Figure 6 is an enlarged fragmentary view taken on line VI—VI of Figure 3, with the table structure removed.

Figure 7 is an enlarged detailed view.

As shown on the drawings:

There is shown in Figure 1 a portion of a Fourdrinier paper making machine of the removable table type embodying the principles of our invention.

The reference numeral 1 indicates a supporting structure as a whole, comprising a pair of longitudinal I-beams 2 spaced apart by means of transverse beams 3 bolted thereto. Mounted on said supporting structure 1 are a plurality of transverse I-rails 4, which together with the I-beams 2 form a substructure

on which a table structure 5 is adapted to be supported when in operative position. The rails 4 also serve, as will later be explained, as tracks on which the table is adapted to be moved when a wire is being changed. Said table structure 5 comprises a pair of table rails 6 supporting the usual table rolls 7 and suction boxes 8. A wire guide roll 9, a wire stretch roll 10 and an inside wire roll 11 are indicated on the drawings. A breast roll 12 and a lower couch roll 13 are supported independently of the table structure. A wire 14 is shown in normal position passing around said breast and couch rolls and over said table rolls. It will be noted that the rolls 10 and 11 are so positioned as to carry the lower run of the wire below the level of the bottom flanges of the tracks 4. The importance of this feature will be explained later. Return wire rolls 15, supporting the lower run of the wire 14, are journalled in bearings carried by the supporting beams 2. Any suitable shaking mechanism may be associated with the breast roll or table structure or both.

The table rails 6 are supported in operative position by flanged rollers 16 running on said tracks 4, said rollers being operated by means of a driven shaft 17 to cause the table structure 5 to roll as a unit over the tracks 4.

The table rails 6 are tied together by means of transverse bars 18 to form the unitary table structure 5. Said table rails 6, which are preferably formed of channel iron, support from their lower flanges a plurality of hollow brackets 19, which form the bearings for the driving shaft 17. The flanged rollers 16 are adapted to be housed in pairs within said hollow brackets 19. A collar 20 on each side of said hollow bracket 19 takes up any end thrust on the shafts 17 and holds the rollers 16 against binding. The hollow bracket 19 on the back end of each of the beams 18 is drilled and threaded to receive a locking screw 21 secured to the track 4, for locking the table structure in place.

The tracks 4, which will hereafter be designated as the inner tracks, are each pivotally mounted upon the front side of the machine by means of a swivel bracket 22 enclosing a pivot pin 23 secured to the I-beam 2 by means of a supporting bracket 24. An outside track 25 is slidably mounted beside each of the tracks 4 upon rollers 26 and 31 carried in a frame 27. Said frame 27 is provided with a

flanged base portion 28 bolted to said bracket 24 and the flange of the beam 2, and is formed with a pair of upstanding sides 29 and 30. The flanged rollers 26 and 31 are journaled 5 in said sides 29 and 30, the roller 26 forming the support for one end of the I-beam track 25 when in normal position. A pair of small bevelled rollers 32 are rotatably mounted directly above the rollers 26 and 31 on one side 10 of the track 4. Said rollers 32 are mounted on pins 33 adjustably secured in the side 29 of the frame 27. Said rollers 32 are so positioned as to bear against the top face of the lower flange of the track 25, and thus support 15 said track in unbalanced position. The track 25 is at the same time held against the rollers 26 and 31 between the flanged ends thereof to prevent said track from jumping off the rollers 26 and 31 when being moved in and 20 out of the machine. A pair of oppositely positioned adjusting bolts 34 extend from the frame sides 29 and 30 to abut each side of the web of the track 25, thereby holding it in vertical position. When the track 25 is in 25 operative position it extends between the beams 2, the back end of said track resting on a curved surface 35 formed in a frame 36 secured to the rear beam 2. Said frame 36 also carries a pair of adjusting bolts 37 similar to the bolts 34. The free end of the track 4 in operative position rests upon an elevated seat 38 formed on the frame 26. A locking pin 39 serves to lock said track 4 in operative 30 position to the frame 36.

35 It will be noted from Figure 6 that the inside tracks 4 are a trifle higher than the sliding tracks 25 in order to permit the tracks 25 to be easily moved into an outer position. Furthermore, the inner end of each track 25 is slightly tapered on its top face as at 40 (Figure 7) to provide a gentle slope extending below the face of the adjoining track 4. There is, therefore, no possibility of jolting 45 as the table structure 5 is rolled out and the rollers 16 roll off the tracks 4 onto the tracks 25.

During the operation of the paper machine, both sets of tracks 4 and 25 are adapted to be positioned between the front and 50 rear I-beams 2 in locked position. When a wire is to be changed the tracks 25 are pulled out to the extended position and the table structure 5 rolled out on it. In this connection, a fixed, stationary support 41 is provided 55 for the free end of each of the tracks 25 in extended position. It will be understood of course, that before the table structure 5 can be moved out, the breast roll 12 and couch roll 13 must be moved toward each other so 60 as to give the necessary slack in the wire. The wire is then suitably suspended away from the table structure 5 and said table structure rolled out onto the tracks 25. The inside tracks 4 are then unlocked and swung parallel 65 to the beam 2, after which a new wire is

strung in place and the tracks 4 swung back into locked position. The table 5 may now be rolled back over the tracks 25 onto the tracks 4 and the tracks 25 pushed into position alongside the tracks 4. The paper machine may be operated with the tracks 4 and 70 25 in this position for the reason that the lower run of the wire extends below said tracks and therefore does not interfere therewith. 75

It will thus be apparent that we have provided a simplified structure whereby a considerable amount of time and labor is saved in the changing of wires on the paper machine. It should be particularly noted that 80 the pivotally mounted tracks 4 form a permanent part of the table sub-structure on which the table unit is adapted normally to rest. The only steps necessary therefore in changing the wire are the pulling out of the 85 beams 25, the rolling out of the table structure by means of the power driven shaft 16, the swinging of the tracks 4 parallel to the beams 2 while the new wire is being strung in position, the swinging back of the tracks 90 4 into locked position, the rolling back of the table structure and finally the pushing of the tracks 25 back into position adjacent the tracks 4. Since the tracks 25 are mounted on 95 roller bearing surfaces and are supported in unbalanced position by means of the spaced bevelled rolls 32 and the rolls 26 and 31, the effort required in moving the tracks 25 into and out of position is very slight. 95

We are aware that many changes may be 100 made, and numerous details of the construction may be varied through a wide range without departing from the principles of this invention, and we therefore do not purpose limiting the patent granted hereon, other- 105 wise than necessitated by the prior art.

We claim as our invention:

1. In a paper making machine, a table structure and track members on which said structure may be removed comprising pivoted inner members and slidable outer members adapted to form parallel extensions therewith, and to be normally positioned alongside of and parallel to said inner members. 115

2. In a paper making machine, a table structure, a wire associated therewith, and track members on which said structure may be removed comprising pivoted inner members and slidable outer members adapted to 120 form parallel extensions therewith and to be normally positioned alongside of and parallel to said inner members above the lower run of the wire.

3. In a paper making machine, a removable type Fourdrinier section comprising a sub-structure, a laterally removable table structure, tracks pivotally mounted on said sub-structure and forming the normal support for said table structure in operative 125 130

position and other tracks mounted for rolling movement on said sub-structure and adapted to be extended laterally to form a support for said table structure when in removed position.

- 5 4. In a paper making machine, a removable type Fourdrinier section comprising a sub-structure, a laterally removable table structure, tracks pivotally mounted on said 10 sub-structure and forming the normal support for said table structure in operative position and other tracks mounted for rolling movement on said sub-structure and adapted to be extended laterally to form a support 15 for said table structure when in removed position, and guiding and supporting means for maintaining said last mentioned tracks in level upright position during movement of said tracks.
- 20 5. In a paper making machine of the removable Fourdrinier type, a laterally remov-

able table unit, tracks on which said table may be removed comprising inner pivotally mounted rails and outer laterally movable rails having lower flanges, rollers for supporting said outer rails and bearing rollers adapted to contact the upper surfaces of the lower flanges of said outer rails to hold said outer rails level during movement of the same.

25 6. In a paper making machine, a table, a wire associated therewith, inner pivotally mounted track members normally supporting the table and other slidably mounted track members adapted to be moved laterally for supporting said table in removed position, all of said track members being positioned above the lower run of said wire.

30 In testimony whereof we have hereunto subscribed our names.

ALONZO ALDRICH.
EARL E. BERRY.
